UNITED STATES PATENT OFFICE.

WILLIAM ALFRED STEPHENS, OF LONDON, ENGLAND, ASSIGNOR TO THE BRITISH
SURE SEAL COMPANY LIMITED, OF LONDON, ENGLAND.

METHOD OF AND APPARATUS FOR MANUFACTURING CLOSURES FOR CONTAINERS.

Application filed July 22, 1927, Serial No. 207,795, and in Great Britain August 16, 1926.

This invention relates to the manufacture of closure devices for bottles, jars or the like.

It is usual practice to utilize as a closure for a bottle, jar or the like, a closure referred

5 to in the trade as the "Phoenix" closure which includes a cap (termed in the trade "an inner") which is secured to the container with a flanged jointed locking ring (termed in the trade "a band") which engages over the periphery of the cap, the free edge or the depending edge of the ring being ultimately spun or pressed in under a shoulder on the container to secure the cap thereon, the ring then being of channel form.

10 15 A locking ring is usually stamped out of strip material, and includes a slot at the one end, hereafter termed the "tail", cut transversely of the strip and a tongue cut longitudinally at the other end, hereafter referred 20 to as the "head". To form the ring from the strip the latter is curled until the tongue of the head is hooked into the slot in the tail, then partially uncurled to bring the slot to the root of the tongue, and the overlapping 25 portions being then pressed together to secure the linked ends. When a tongue is raised from the strip the sliding of the slot in a direction for uncurling is opposed by frictional resistance occurring by the interlaced

30 relation of the part of the tail of the strip which, though over the head of the strip is under the tongue raised therefrom, hence small variations occur in the diameter of the finished product.

35 The main object of the present invention is to provide means of expediting with accuracy the several operations pertaining to the jointing of locking rings.

Another object is to effect the linking and 40 jointing without uncurling the strip at all.

Another object of the invention is to improve the method of feeding strips to apparatus for opening up the tongues in particular in feeding strips to automatically operated machines which effect the tongue opening, curling and jointing operations, so that the strips are fed automatically in quick succession synchronously with the several operations thereby assuring a maximum output.

45 50 Another object of the invention is to produce a closure of the Phoenix type in which the "band" is always tightly embracing the "inner".

Another object of the invention is to construct a unit apparatus in which the strip

blank from which a locking ring is made can be associated with a cap or "inner" in the production of a Phoenix cap by curling and linking on the cap itself.

In accordance with the present invention 60 a method of jointing the ends of such locking rings consists essentially in opening up and bending back the tongue through an obtuse angle so that the tip stands up clearly from the head of the strip and then linking the 65 ends curling the strip so that the slot in the tail is first disposed over the tongue tip, and then slidden down to the root of the tongue, thereafter the ends are secured by returning the tongue to its pristine position under pressure, whereby it will engage over the tail end 70 of the ring, thereby locking the linked ends together.

By so opening up the tongue the subsequent operations, of setting the inner in 75 the jointed ring even if manually effected, will be greatly facilitated, and in addition, the finished article will not be distorted to the almost flat elliptical shape so often occurring—from the manual operations of curling 80 and linking. Moreover, the slot is in every case freely brought to the root of the tongue, hence products of uniform diameter are obtained.

85 From the present invention there also evolves a novel method of associating a cap and ring, e. g. in making a Phoenix closure, consisting in curling the strip from which the ring is made actually on the cap and jointing it thereon, the tongue being set 90 back through an obtuse angle as hereinbefore described, and the result of this method is to obtain an extraordinary tight fitting for the ring on the cap, and it may here be mentioned that in the usual manual operation 95 of setting a locked ring about the cap, it frequently happens that there is not at all a tight fit, due in some measure to the distortion of the ring during curling and hammering, also to the variation in the entry 100 of the tongue in the slot.

105 Apparatus for opening up the tongues of strips at an obtuse angle through which it is desired to set back the tongue in accordance with the present invention comprises a slotted platform and an associated plunger member reciprocal through the slot and set with regard to the platform at an acute angle corresponding to the slot of the platform and the plunger member being of a 110

shape to register with the gap in the strip formed as a result of cutting the tongue, so that as the plunger is projected therethrough the platform turns back and sets the tongue at the required angle to the strip.

In the accompanying drawings is shown by way of example apparatus embodying the devices hereinbefore referred to connected and operable to as to effect the locking of a band on an "inner" in one continuous movement from a single control.

Fig. 1 is a plan of the apparatus as a whole;

Fig. 2 is an elevation looking in the direction of the arrow II of Fig. 1;

Fig. 3 is an elevation on the line III—III of Fig. 1;

Fig. 4 is an elevation looking in the direction of the arrow IV; showing only the cap or "inner" carrier and the operating means therefor;

Fig. 5 is an end view of the cap carrier construction shown in Fig. 4;

Fig. 6 is a section elevation to an enlarged scale showing the electro-magnetic means for maintaining strips straight on the platform;

Fig. 7 is an elevation on the line VII—VII of Fig. 6; and

Fig. 8 is an end view of the holder.

The apparatus as shown is a complete unit for treating strip blanks to form them into jointed rings, or for treating strip blanks whilst associated with caps or inners so as to produce in a complete sequence of operations a Phoenix closure ready to be applied to a container.

The apparatus comprises two vertical supports 1, 2, mounted on any suitable base or table, not shown, by feet 1^a, 2^a, respectively, in which are formed bearings for a main shaft 3, a transmission shaft 4 and a hollow shaft 5, the shaft 5 being carried in higher parts 1^b, 2^b of the supports as clearly shown in Fig. 2 the higher part 1^b also forming a support for a timing gear T hereafter referred to.

On the shafts 3 are arranged cams 6, 7, 8, 9, 10 and 11. The cam 7 controls the strip feeding mechanism which includes the bell crank 12 formed at its free end as a fork indicated at 13 which straddles on pin 14 depending from a slide 15 which latter is movable to and fro along the platform 16 as the bell crank 12 is oscillated. The rear part of the slide 15 includes an upstanding abutment 17 for engaging the tails of the strips S, as each becomes lowermost of the pile, see Fig. 3, arranged on the platform. The strips S are not included in Fig. 1 for sake of clearness.

As shown, the platform is of rectangular form being carried on a standard 16^a and an arm 16^b carried by the part 2^b of the support

2. At the forward end the platform is

forked, see Figs. 1 and 7, and within the fork is lodged the top end of a plunger barrel 18 bored for the projection therefrom of a plunger 19, see Fig. 6, which is operated when the head of the strip comes over the plunger and turns back the tongue to the desired angle.

This part of the apparatus which sets the tongue at the desired angle to the strip may be used separately for expediting the usual subsequent hand operations of curling, linking, and jointing locking rings, as hereinbefore explained.

A further increase in speed of operation may be obtained by increasing the length of the slot so as to give a larger limit for the tongue tip to meet and enter the slot, thereby facilitating the linking operation.

Now in order that tongue turning gear may be supplied automatically and so that a maximum output obtains, the strips are arranged in piles over the platform, the tails being at a higher level than the heads and the tongue of each strip overlying the head of the strip next above. To this end there is provided at the rear part of the platform 16 an inclined support 20 for the tails of the strips S, see Fig. 3. The arrangement of this support 20 is such that when the abutment 17 of the slide 15 is in the rearward limit position a strip S' is engaged by the abutment, the head of the strip being juxtaposed to a gate member 21. The superimposed strips are arranged in overlapping relation with all their tails resting on the support 20 and their heads underlapping the tongues of the next undermost strips.

The cam 7 which operates the bell crank 12 has two protuberances in order that there shall be a two-step progression of the slide 15. The first step places the head of the undermost strip over the plunger 19, the gate member 21 having been automatically lifted sufficiently to permit this progress of the lowermost strip.

The position of the abutment 17 when the head of the strip is over the plunger, is indicated at 17^a, Fig. 3, and the second step effected by the cam 7 causes the abutment 17 to move to the position 17^b as a result of which the head of the lowermost strip is pushed clear from the platform, this new position of the strip being clearly indicated in Fig. 6 by the reference S'. The overhanging head of the strip is engaged by a spring-pressed finger 22 on a rotatable holder H hereafter referred to, which in rotating withdraws the strip from the platform. The strip in being dragged from the platform by the holder H drags with it by friction the strip next above, indicated at S², Fig. 6, but as the gate 21 has been lowered the strip S² is arrested and then takes up the position originally held by the strip S'. In

the meantime the abutment 17 is returned to the initial position ready to push forward strip S².

The operation of the gate 21 is preferably controlled by trip gear including an abutment 23 indicated in Fig. 2 and diagrammatically indicated in Fig. 6, arranged on the holder H and a lug 24 adjustably disposed on an arm 25 to which the gate is secured, the arm being pivoted at 26 on the platform.

Referring now to the means for curling and linking the strip after it has left the platform, and which includes the holder H.

15 The controlling members of this mechanism are the cams 8, 9, and the timing gear T, the holder H is mounted at one end of the hollow shaft 5 and is disposed in alignment with the platform so that its finger 22 can, 20 as aforesaid, engage and pull a strip from the platform, and it will be noticed that the arrangement of the holder is such that the platform is not tangentially disposed with regard to the holder. This assures the head 25 of the strip striking the bevelled tip of the finger 22 thereby depressing the finger until the slot behind the tongue is in register, at which movement the finger projects therethrough to pull the strip as aforesaid. Inci- 30 dentally this arrangement imposes a tension in the strip as it is being curled round by the holder. At high speed, however, a further braking device such as 59 hereafter referred to is employed.

35 The platform is provided at its ends with plates 27 indicated clearly in Figs. 2, 6 and 7 which overlap the bifurcated ends of the platform and with them form guides within which the edges of the strip are held while 40 the plunger 19 turns back the tongue and are constrained to pass in leaving the platform. These plates 27 may be constructed and the plunger so formed as to cut out the tongue from a blank strip as well as turning it back.

Alternatively, the blanks may be scored to demark the tongue, and then the tongue can be freed and turned back by a plunger operating with plate 27 as aforesaid.

50 Now in order to mechanically assist the engagement of the strip on the finger 22 and to effect the linking of the strip ends, two spaced guide plates 28 and 28^a including cam faces 29 are arranged about the holder, 55 the cam faces merge into an internal circular periphery disposed in proximity to the path which will be taken by the head of the strip as impelled by the movement of the holder, thereby tending to prevent displacement of 60 the head of the strip from the finger and to constrain the head of a strip leaving the platform on to the finger 22. This arrangement is clearly shown in Fig. 6.

It will be clear therefore, that the function 65 of the holder H in the form shown, is to

pull the head of the strip round through a circular path in order to eventually bring the head beneath the tail in order that the slot in the tail can be pressed over the tongue in the head. It is convenient therefore to 70 adopt a holder of drum-like form to include the required anvil surface to support the ends of the strip during the pressing and hammering operation; such a holder acts as a former for the strip and prevents sagging 75 between the head and the platform.

The plates 28, 28^a, are secured together at the bottom by screws and distance pieces, not shown, but in their upper corners the plates are used as supports for pivotal axes 80 of the tongue opening plunger barrel 18, and the pressing and hammering means indicated at 18^a and 36 respectively, see in particular Fig. 3.

By pivoting the barrel of the plunger 85 and providing it with a slotted quadrant 30, the position of the barrel can be angularly set by loosening and then tightening the nut member 31 as will be well understood, the plunger is operated by a pair of cams 32 on 90 the shaft 4 acting with bowls 33 carried on trunnion members 34, connected to the plunger and passing through a slot in the barrel.

The strip having been pulled by the holder 95 through 360°, that is until the head is beneath the tail, the cams 29 on the guides 28 again operate and this time function to push the tail on to the head so that the desired tongue and slot engagement results. Then 100 to press the two ends of the strip together to form a jointed locking ring, the bell crank including forked arm 35 and arm 35^a pivoted at 36 in the guide plates, is provided. The arm 35 descends through the operation 105 of the cam 9 which rocks the lever 37 about its pivot 38 thereby causing an upward movement of the rod 40 and a corresponding rocking of the lever arm 35^a. The distance between the arms of the fork is such that 110 they straddle the tongue of the strip and finger 22 of the holder H.

It will be noted that the arms 35 have each a concave portion 41 of an arcuate form which is concentric with the holder when the lever arms 35 press against the linked ends of the strip. Whilst the ends are thus held pressed together the cam 8 rocks lever 42 about its pivot 43 and by reason of the link connection at 44 causes the bell crank 45 to rock. At the end of the bell crank is a link 46 which is pivotally connected by a second link 47 itself pivoted between the pressing arms 35. It will be observed therefore that with the lever arm 35 in the pressing position the pivotal axis thereon of the link 47 will be juxtaposed to the root of the strip and therefore that as the lever 45 rocks as a result of the cam action referred to the resultant movement of the link 46 causes the 120 125 130

link 47 to move up against the upstanding tongue and then in a somewhat kneeling movement press over and hammer down the tongue.

- 5 The operation of linking, pressing and hammering the strip is then finished and a jointed locking ring is formed. It then remains to eject the strip from the holder H and this is effected by the cam 6 through 10 the bell crank 48 which operates a rod 49 passing through the hollow shaft 5 and the holder H and terminating in a plate 50 having peripheral claws 51 for the reception of which the holder H is slotted so that 15 in fact the claws form part of the periphery of the holder, the claws being shouldered as indicated at 52 against which the strip abuts when disposed about the holder so that the 20 operation of the cam 6, as aforesaid, effects a peripheral ejection of the jointed ring from the holder.

The rotation of the holder H is effected from the timing gear T through a pinion 25 53 carried by the hollow shaft 5 and the arrangement is such that the holder is stationary during the pressing and hammering and ejection operations.

It may here be mentioned also that while 30 the holder is stationary and just prior to ejection a strip is fed forward by slide 15 through the second progressive step from the platform 16 to the spring pressed finger 22 of the holder so that the new strip overlies the curled strip and is ready to be engaged by finger 22 immediately the curled strip has passed over the finger as a result 35 of the ejector action.

The timing gear T aforesaid, which regulates the rotation of the holder H, includes a 40 toothed timing wheel 54, on which is coaxially mounted a diametrical arm 55 carrying at one end a ratchet 56 preferably mounted for adjustment e. g. on an eccentric bush, engaging the timing wheel teeth, this 45 timing wheel being in mesh with the pinion 53 associated with the holder H. The other end of the diametrical arm 55 is adjustably connected by a pitman or connecting rod 57 to a crank member e. g. disc 58, on the transmission shaft 4, or driven synchronously therewith, the arrangement being such that as the crank member 58 rotates it oscillates the arm on the timing wheel 54 and causes the ratchet 56 carried thereon to alternatively 50 engage the teeth of the timing wheel and to slide thereover. Each oscillation of this radius arm 55 is of an amplitude of 90° so that there are four revolutions of the holder H for each single revolution of the timing 55 gear, and at the end of each revolution the holder is in such position to correctly present the tongue and slot of a strip curled thereon to the pressing and hammering gear.

60 However, to prevent overrun of the holder 65 a mechanically operated friction brake, e. g.

the band brake 59 carried on support 60 may be employed on hollow shaft 5, alternatively a positive register gear may be employed including, for instance, a notch in the flange H' of the holder H (see Fig. 2) disposed 70 to receive a pivoted latch or catch indicated at 61, Figs. 2 and 6, retractable from the slot automatically at the commencement of the next rotary movement.

The cams hereinbefore referred to for 75 operating the pressing and hammering devices are preferably set so that the pressing and hammering is effected at the same time as the feeding device moves a strip forward to have the tongue opened back, the holder 80 at this time being stationary, and the second movement of the strip which finally disposes its head over the spring pressed finger on the holder is simultaneous with the ejection of the previously jointed ring, and in between 85 these operations the holder rotates to effect the curling and linking operations.

It will be noted that the shaft 3 is connected to the shaft 4 for example, with pinions 62, 63, so that the shaft 4 is driven at 90 the same speed as the shaft 3. It follows, therefore, that the control of the speed of the shaft 3 controls all the operations of the machine.

The apparatus described is suitable for 95 the formation of a "Phoenix" closure and for other forms of closures including a cap and ring by varying the form of the holder as will be readily understood. It is merely necessary to lodge the cap or "inner" about 100 the holder and then the strip may be curled about the cap.

To this end there may be arranged opposite the holder H a tilted carrier C of U shape normally disposed at the end of an inclined chute 64 down which the "inners" or caps are fed for successive reception by the carrier C.

The caps are fed to the holder so as to be lodged within the guide plate 28 and against the ejector plate 50 against which it is held by cap feeding plunger 67 (hereafter referred to), see Fig. 8.

In this position the cap is retained in desired relation with the anvil surface of 115 holder H so that a strip is curled about the cap, the latter being located from one edge of the strip so as to be ready for treating in flanging machine, e. g. a dial feed press.

120 Although a full description of the carrier and its pertaining parts is herein given for purposes of full explanation, it will be understood that the carrier constructed and operating as herein described is the subject of co-pending patent application Serial No. 125 207,796 for an invention entitled "Cap feeding mechanism for closures of bottles, containers or the like".

130 The carrier is provided with a sleeve 65 in which is slidably disposed a second tube

66 within which is the rod 67 passing through both tubes and through the carrier C, and connected to the second tube by a spring 68. The function of this rod is to finally eject a cap from the carrier C on to the holder H, and it is operated by the cam 11 on the main shaft 3 through the bell crank 11^a in exactly the same way as the ejector rod 49 before referred to.

10 The cam gear is such that the inner sleeve 66 first moves the carrier C up to the holder H. At this moment the effort of placing the cap on the holder compresses the spring 68 on the axial rod 67 with the result that the rod 15 moves onward and centrally taps the cap on to the holder H so that the cap lies flatly thereon, it being understood that in the quiescent position of the rod it is withdrawn by spring 68 acting between sleeve 66 and 20 abutment 69 from the face of the carrier.

Associated and movable synchronously with the carrier is a cut off member, e. g. a plate 70 which, as the carrier moves to the holder, cuts off the chute until the carrier 25 has returned to position to receive the next cap.

In front of the carrier C is a guard plate 71 which prevents caps jumping out as they roll in from the chute 64, the plate being pivoted at 72, and the carrier is provided with a finger 73, which as the carrier moves forward displaces the guard plate to the position, shown in dot and pick lines Fig. 5, where it is out of the path of advance to the 35 holder H.

The guard plate is conveniently provided with wings 74 which straddle the holder H and form with the plate a hopper device for guiding finished closures ejected from the 40 holder H down through a conduit 75 (Fig. 1).

At the side of chute 64 is a spring controlled arm 76 (Fig. 4) pivoted at 77 which operates as a selector by reason of a pin 45 78 at its extremity intercepting the foremost cap in the chute and holding it back clear of the carrier C thereby definitely separating the cap in the carrier from those following. Such arrangement eliminating the possibility 50 of edge engagement of the two caps as the carrier moves forward probably resulting in tipping of the cap in the carrier owing to the frictional adhesion by reason of the rough edges.

55 To permit movement of the caps in the chute 64 to the carrier C, cam 10 is mounted on shaft 3 and is designed to lift the lever 76 through the agency of the abutment 80 as soon as the carrier has moved forward 60 thereby permitting the next cap to roll to the cut off plate 70 ready to enter the carrier when it is again retracted back to alignment with the chute 64.

In practice caps vary as regards construc-

tion, and the strips vary as regards width. 65 In order to accommodate different types of caps the front face of the holder may be dished, or the holder may be hollow and have its engaging face constituted by a movable ring or rings so that an end face may 70 be formed on the holder to correspond to the cap which is going to be used, and as regards the accommodation of strips of varying width, or wherein the tongue and slot are not centrally disposed, the rear face of 75 the holder may be provided with a movable flange adjustable on the holder, or it may be substituted by other flanged members so as to act as a stop or guide for the strip on that side of the holder.

80 Electro-magnetic means may also be included, as shown for example in Figs. 2, 3 and 6, but omitted from Fig. 1 for sake of clearness, for maintaining the strips flat on the platform when being pushed along by 85 the abutment 17.

81 As clearly illustrated in Fig. 6 the poles 82 are arranged beneath the platform and energized from the coil 83 through suitable circuits controlled by the rotation of the 90 shaft 3. The platform 16 may also be provided with an eliminator plate 83 clearly shown in Fig. 6 cut away in the centre (for the passage thereunder of strip tongues) leaving prongs which are of a length to engage, for example, the top strip when three overlapped strips attempt to pass thereunder. With such an arrangement when one strip has arrived at the gate the third will 95 be held up by the eliminator plate 83.

100 84 and 85 (Fig. 1) are auxiliary supports for the shafts 3 and 4.

Generally speaking, and as already indicated, it is preferred to operate all the members by cam actuating gear, the retraction 105 of the different members being assured by springs, or equivalent resilient means, the operation of the several parts being effected from a mechanical motor, by manual power through suitable gearing, or by magnetic or 110 electro-magnetic or fluid control. Various modifications, however, may be effected without departing from the spirit of the invention, for instance, the ejection and the feeding of the cap and strips may be effected 115 by a magnetic or electro-magnetic apparatus.

120 Electrical circuits may also be included to stop the machine when the supply of strips or caps has run out. Conveniently, the centre of the cap holder H or the ejector plate 50 may form one terminal of such an alarm circuit and the axial plunger of the carrier as the other, so that if the two meet as the result of the absence of a cap the 125 circuit is completed. To this end the centre of holder H may be provided with an insulating bushing within which is the termi-

nal lying just behind the holder face so that caps placed in the holder do not come in contact with it.

An apparatus comprising integers hereinbefore described provides a continuous means of feeding the strips and caps so that they, in proper time, arrive at the holder so that a strip can be jointed around a cap and ejected in locked association, all automatically effected, thereby, enormously expediting the production of these articles in comparison with the output at present obtained by the existing usual hand operations.

15. What I claim is:

1. A method of jointing the ends of a strip to form a locking ring of a closure for containers, which consists in providing the strip near one end with a tongue, and near 20 the other end with a slot, setting back the tongue through an obtuse angle, and linking the ends by curling the strip until the slot passes over the tip of the tongue to the root, and returning the tongue to its pristine 25 position under pressure.

2. A method of associating a cap and ring to form a closure for a container consisting in providing the strip from which the ring is made with a tongue near one end, and with 30 a slot near the other end, setting back through an obtuse angle the tongue of the strip, linking the ends of the strip by curling the strip on the cap until the slot passes substantially to the root of the tongue, then 35 returning the tongue to pristine position under pressure.

3. Apparatus for turning back through an obtuse angle the tongue in the head of a strip blank including in the tail end a slot, 40 in preparation for curling the strip into a jointed locking ring for a closure of a container, comprising in combination a slotted platform, a plunger set at an acute angle to the platform corresponding to the said obtuse 45 angle, means for reciprocating the plunger through the slot in the platform and guiding means for the strip adapted to hold the strip to the platform during the operation of the plunger.

50. 4. Apparatus for turning back through an obtuse angle the tongue in the head of a strip blank including in the tail end a slot, in preparation for curling the strip into a jointed locking ring for a closure of a container, 55 comprising in combination a slotted platform, a plunger set at an acute angle to the platform corresponding to the said obtuse angle, means for reciprocating the plunger through the slot in the platform, guiding 60 means for the strip adapted to hold the strip to the platform during the operation of the plunger, automatic means operating in two steps for feeding a strip along the platform through the guides to present the head there- 65 of to the plunger and after the plunger is

retracted for further pushing the strip until the head overhangs the platform, and means for engaging and withdrawing each strip as it is pushed to the overhanging position.

5. Apparatus for turning back through an obtuse angle the tongue in the head of a strip blank including in the tail end a slot, and for curling the strip into a jointed locking ring for a closure of a container, comprising in combination, a slotted platform, a plunger, set at an acute angle to the platform corresponding to the said obtuse angle, means for reciprocating the plunger through the slot in the platform, guiding means for the strip adapted to hold the strip to the platform during the operation of the plunger, automatic means operating in two steps for feeding a strip along the platform and through the guides to present the head thereof to the plunger and for pushing the strip after the plunger is retracted so that the head overhangs the platform, rotary means of the diameter of the finished ring for engaging the overhanging head of the strip for withdrawing the strip from the platform, and for curling the strip until the ends are linked, and pressure means for returning the tongue to pristine position.

6. Apparatus for turning back through an obtuse angle the tongue in the head of a strip blank including in the tail end a slot, and for curling the strip into a jointed locking ring, comprising in combination a slotted platform, a plunger set at an acute angle to the platform corresponding to the said obtuse angle, means for reciprocating the plunger through the slot in the platform, guiding means for the strip adapted to hold the strip to the platform during the operation of the plunger, automatic means operating in two steps for feeding a strip along the platform and through the guides to present the head to the plunger and for pushing the strip so that the head is free of the platform after the plunger has operated, a rotatable drum like former of the diameter of the finished ring, including a spring pressed finger projecting from its cylindrical face, means for deflecting the overhanging head of the strip onto and down the finger, means for rotating said former until the ends are linked and pressure means for returning the tongue to pristine position.

7. A method of turning back through an obtuse angle, in automatic succession, the tongues in the heads of strip blanks, each including in the tail end a slot consisting in arranging the strips in a pile, the tongues of each strip overlying the head of the strip next above, sliding the lowermost strip forward, thereby frictionally dragging and separating the next lowermost strip from the pile, turning back through an obtuse angle the tongue of the forward strip, pulling clear of the pile each forward strip after

the tongue has been turned back, and simultaneously sliding forward the next lowermost strip, whereby all the strips in the pile are similarly treated in automatic succession 5 from the bottom of the pile.

8. Apparatus for turning back through an obtuse angle the tongue in the head of each strip blank including in the tail end a slot, of a stack of superposed blanks, and for curling 10 each strip into a jointed locking ring for a closure of a container, comprising in combination a slotted platform, a plunger set at an acute angle to the platform corresponding to the said obtuse angle, means for reciprocating the plunger through the slot in the platform, means for holding the strip to the platform during the operation of the plunger, automatic means operating in two steps for feeding the lowermost strip along the 15 platform to present the head to the plunger and for pushing the lowermost strip so that the head overhangs the platform after the plunger is retracted, a gate member movable relatively to the platform forming an abutment for the head of the next lowermost strip, means for lifting the gate preparatory to the first movement of the feeding means and for returning the gate immediately thereafter, rotatory means of the diameter of 20 the finished ring for engaging the head of a strip overhanging from the platform, and for withdrawing and curling the strip until the ends are linked, and pressure means for returning the tongue to pristine position.
9. Apparatus for turning back through an obtuse angle in automatic succession tongues in the heads of strip blanks, each including in the tail end a slot and for curling them into jointed locking rings for closures for 25 containers, comprising in combination a slotted platform, a plunger set at an acute angle to the platform corresponding to the said obtuse angle, means for reciprocating the plunger through the slot in the platform, guiding means for the strip adapted to hold the strip heads to the platform during the operation of the plunger, a support for the tail ends of the strips at a level 30 above the platform, automatic means operating in two steps for feeding the lowermost strip along the platform and through the guides to present the head to the plunger and for pushing the strip after the plunger is retracted so that the head overhangs the platform, said feeding means including a slide movable over the platform and an upstanding abutment for engaging the tails of the strips as they fall successively from said support, a gate member movable relatively 35 to the platform forming an abutment for the head of the next lowermost strip, and means for lifting the gate preparatory to the first movement of the feeding means and for returning the gate immediately thereafter, and rotatory curling means of the

diameter of the jointed ring for engaging each overhanging strip head.

10. Apparatus for jointing the ends of a locking ring comprising in combination means for turning back through an obtuse 70 angle the tongue of the strip from which the ring is to be made, including a slotted platform, a plunger set at an acute angle to the platform corresponding to the said obtuse angle, means for reciprocating the plunger through the slot in the platform, guiding means for the strip adapted to hold the strip to the platform during the operation of the plunger, curling means adapted to move the head of the strip through a circular path of a diameter equal to the jointed ring until the head is disposed beneath the tail and the ends linked by the tongue entering the slot therein, pressing means obtaining a close association of the linked head 85 and the tail, and means for returning the tongue to pristine position over the tail whilst the close association is maintained to finally lock the ends of the strip.

11. Apparatus for jointing the ends of locking rings, comprising in combination a slotted platform, a plunger set at a predetermined acute angle to the platform, means for reciprocating the plunger through the slot in the platform, guiding means for the strip adapted to hold the strip to the platform during the operation of the plunger, automatic means operating in two steps for feeding a strip along the platform to present the head to the plunger and for pushing 100 the strip so that the head overhangs the platform after the plunger has operated, a rotatable drum like former of a diameter of the jointed ring including a spring pressed finger projecting from its cylindrical face, means for deflecting the overhanging head of the strip on to the finger, presser arms for engaging the cylindrical face of the former locally to the finger and to each side thereof, and a presser arm for 105 simultaneously engaging the intermediate area including the finger.

12. Apparatus for jointing the ends of locking rings, comprising in combination a slotted platform, a plunger set at a predetermined acute angle to the platform, means for reciprocating the plunger through the slot in the platform, guiding means for the strip adapted to hold the strip to the platform during the operation of the plunger, 115 automatic means operating in two steps for feeding a strip along the platform to present the head to the plunger and for pushing the strip so that the head overhangs the platform after the plunger has operated, a rotatable drum like former of the diameter of the jointed ring including a spring pressed finger projecting from its cylindrical face, means for deflecting the overhanging head of the strip on to the finger, a bell 120

125

130

crank lever, a forked arm to said lever formed to straddle the finger and lie on the cylindrical surface of the former local thereto, a link member pivoted within the fork, and means for moving said link about its pivot on to the cylindrical surface so as to return the tongue to pristine position and depress the finger.

13. Apparatus for jointing the ends of locking rings, comprising in combination a slotted platform, a plunger set at a predetermined acute angle to the platform, means for reciprocating the plunger through the slot in the platform, guiding means for the strip adapted to hold the strip to the platform during the operation of the plunger, automatic means operating in two steps for feeding a strip along the platform to present the head to the plunger and for pushing the strip so that the head overhangs the platform after the plunger has operated, a rotatable drum like former of the diameter of the jointed ring, a spring pressed finger projecting from its cylindrical face, guide plates in close proximity to the former including cam faces adapted to deflect the overhanging head of the strip on to the finger, presser arms for engaging the cylindrical face of the former locally to the finger and to each side thereof, a presser arm for simultaneously engaging the intermediate area including the finger, and ejector, means including abutments operating on the edge of the jointed locking ring.

35 14. Apparatus for associating a cap and locking ring to form a closure for a container comprising in combination a rotatory former for the strip of the diameter of the cap and means for disposing the cap concentric with the former with its flange juxtaposed thereagainst, whereby the strip is curled by the former on the cap flange.

15. Apparatus for associating a cap and locking ring having its tongue turned back through an obtuse angle to form a closure for a container comprising in combination curling means operable about the flange of the cap whereby the strip is curled on the cap flange until the ends are linked and pressure means for securing the linked ends and for returning the tongue of the strip to pristine position.

16. Apparatus for associating a cap and locking ring to form a closure for a container comprising in combination plunger means for setting back the tongue of the strip through an obtuse angle, feeding means for pushing the strip to the plunger and then, after the plunger has operated, on to a position in which the head of the strip overhangs the platform, rotatory means of the diameter of the cap for engaging the overhanging strip and means for holding the cap concentric with the rotatory means and with its flange juxtaposed thereto, whereby

the strip is curled by the rotatory means on the flange of the cap.

17. A unit apparatus for making closures for containers comprising in combination means for turning back through an obtuse angle the tongue on the head of a strip blank, rotatable means for pulling the strip by its head in a circular path of the diameter of the cap of the closure, plunger means for disposing and retaining a cap within the circular path, means for engaging the tongue and slot of the strip when curled about the cap, means for pressing the ends of the strip together and means for returning the tongue to pristine position.

18. A unit apparatus for making closures for containers comprising in combination means for turning back through an obtuse angle the tongue in the head of a strip blank, rotatable means for pulling the strip by its head in a circular path of the diameter of the cap of the closure, consisting of a drum like former including a spring pressed plunger adapted to engage in the gap behind the tongue of the strip and constraining means for deflecting the tail of the strip on to the tongue thereof and for retaining the strip in close association with the former thereby linking the ends of the strip, means axially reciprocable to and from the former for disposing a cap within the circular path, mechanism for intermittently rotating the former so that it is stationary when a cap is fed thereto, presser means associated with the former for locking the linked ends of the strip, means for ejecting the closure from the former when the latter is stationary, and means for simultaneously feeding a successive strip to the former.

19. Apparatus for making closures comprising in combination a drum like former on which the strip blank is curled and to which a cap is held, a plunger carried by the former to engage in the gap behind the tongue of the strip, spaced guide plates (one to each side of the plunger) including cam faces for constraining a strip head on to the plunger and for retaining the strip in close association with the former, presser means operating with the former for locking the ends of the strip, means for intermittently rotating the former so that it is stationary after each curling movement and ejector means operative when the former is stationary.

20. Apparatus for associating a cap and locking ring to form a closure for a container comprising in combination a rotatory former for the strip of the same diameter as the cap and means for disposing the cap concentric with the former with its flange juxtaposed thereagainst, whereby the strip is curled by the former on the cap flange, and ejector means including abutments operating on the edge of the jointed locking ring.

21. A method of associating a cap and locking ring in the formation of a closure for a container, comprising the steps of forming complementary securing means at the ends of the strip from which the ring is made, curling the strip actually on the cap itself, positively moving the ends of the strip towards one another throughout such curling operation until the securing means are linked, and securing the ends of the strip.
